UNITED STATES PATENT OFFICE.

HARRY S. BENJAMIN, OF DETROIT, MICHIGAN, ASSIGNEE TO BENJAMIN MOTOR PRODUCTS CO., OF DETROIT, MICHIGAN, A CORPORATION OF DELAWARE.

INTAKE MANIFOLD FOR INTERNAL-COMBUSTION ENGINES.

Application filed March 3, 1920. Serial No. 362,942.

To all whom it may concern:

Be it known that I, HARRY S. BENJAMIN, a citizen of the United States, residing at Detroit, in the county of Wayne and State 5 of Michigan, have invented certain new and useful Improvements in Intake Manifolds for Internal-Combustion Engines, of which the following is a description.

My invention belongs generally to the 10 class of intake manifolds arranged to conduct the explosive charge of an internal combustion engine from the carburetor to the intake ports. It has for its object the production of such a device adapted to 15 perform the functions set forth in an efficient manner, and which is particularly adapted to more efficiently handle such mixtures carrying the heavier hydrocarbons.

To this end my invention consists in the 20 novel construction, arrangement and combination of parts herein shown and described, and more particularly set forth in the claims.

This application is one of a series of 25 cases including my co-pending applications Serial Nos. 347,586 and 369,264.

In the drawings, wherein like reference characters indicate like or corresponding parts,

30 Figure 1 is a side elevation of a portion of the exhaust manifold with the intake manifold and associated parts in position in relation thereto; and

Figure 2 is a central vertical section 35 through the center of the intake manifold in a lengthwise direction.

In the drawings, 1 indicates the exhaust manifold and 2 the carburetor. Positioned 40 within the exhaust manifold in such manner as to be substantially integral therewith, is a pipe 3 provided with a plurality of branches, for illustration the three branches 4, 5, and 6. The intake manifold proper 7 is provided with extensions 8, 9, and 10 45 adapted to register with and be secured to said extensions 4, 5 and 6 substantially as indicated. The part 8 is preferably centrally positioned above the intake manifold, and is dome-shaped or extended upward 50 from the main body of the intake manifold at that point, so that the incoming charge coming through the neck 11 has a tendency to be carried upward into said dome 8. The two lateral branches 12—12 of the intake 55 manifold are extended outward beyond the

60 pipes 5 and 6, and are connected to the intake ports. Just before the lateral branches 12—12 come into alignment with the pipes 5 and 6, they are reduced to form venturis 13—13, the central line of the reduced portions of the venturis preferably being in proximity to the walls of the pipes 5 and 6 next to the dome 8.

In practice I have formed the pipe 3 65 substantially as shown and of suitable material, and have positioned the same in the core employed in casting the exhaust manifold 1. By this means the pipe 3 is formed substantially integral with the exhaust manifold. Any other means, however, 70 securing the same results would serve the purpose.

In actual practice I have secured satisfactory results by forming the parts substantially as indicated, and of the following 75 dimensions. The diameter of the neck 11, substantially one inch, the diameter of the venturis at the shortest point, substantially eleven-sixteenths of an inch, the diameter of the tube on pipe 3 five-sixteenths of an 80 inch, and the diameter of the intake manifold between the venturis and the intake ports substantially fifteen-sixteenths of an inch.

A device constructed in accordance with 85 these dimensions is adapted for use upon the size or type of car known as the Ford car. The proportions would be varied according to the size of the engine and associated parts.

90 Any preferred means may be employed for firmly and tightly securing the ends of the pipes 4, 5 and 6 to the cooperating extensions 8, 9, and 10. As shown, the extensions 8, 9, and 10 are internally threaded. A co-operating part 14, 15 and 16 provided with a head adapted to receive a wrench, is externally threaded to cooperate with the extensions 8, 9 and 10. A suitable gasket 17 95 may be employed in each case, the shoulder 100 within the parts 8, 9, and 10 being slightly inclined, so that as the nuts 14, 15 and 16 are screwed home the gasket will be forced downwardly and inwardly, snugly embracing the ends of the pipes 4, 5 and 6.

105 The mode of operation is apparent. The incoming charge tends to be carried by its momentum upward into the dome 8, the heavier particles acquiring a greater momentum than the lighter. The capacity of the 110

pipe 4, however, is not sufficient to take the full charge, which is therefore divided and parts of which proceed through the extensions 12—12, through the venturis 13, by the 5 ends of the pipes 5 and 6, and thence to the intake ports. The action is thus that the heavier particles are carried upward through the pipe 4 into the horizontal section of the pipe 3, which is heated by the exhaust gases, 10 said heated gases being conducted through the pipes 5 and 6 and discharged into the path of those portions of the charge which will pass through the parts 12—12 and the venturis 13—13. The venturis are prefer- 15 ably positioned just before a central line through the pipes 5 and 6, the reduced portions thereof serving to increase the velocity of the passing charge, and thus by an action similar to a syphon action, aiding in the de- 20 livery of the heated gases through the pipes 5 and 6.

It will be seen that by my improved device no valves or movable parts are necessary to secure effective operation, which is at all 25 times automatic in its action.

Having thus described my invention, it is obvious that various immaterial modifications may be made in the same without departing from the spirit of my invention; 30 hence I do not wish to be understood as limiting myself to the exact form, construction, arrangement and combination of parts herein shown and described, or uses mentioned.

What I claim as new and desire to secure 35 by Letters Patent is:

1. A device of the kind described comprising an intake manifold provided with a neck adapted to cooperate with a carbureter, a central dome positioned substantially above 40 said neck, and inlet openings in the manifold on each side of said dome, in combination with a cooperating pipe positioned within the exhaust manifold with extensions ar-

ranged to register with said dome and the two inlet openings, means for connecting 45 said extensions to the intake manifold, and venturis positioned in the manifold in proximity to the said two inlet openings.

2. A device of the kind described comprising an intake manifold provided with a neck arranged to receive the charge from a carbureter, a centrally arranged dome above the neck, an intake opening in the manifold on each side of said dome, and venturis positioned in the manifold with the narrowest 50 part thereof near the wall of the intake openings nearest the dome, in combination with an exhaust manifold, a cooperating pipe positioned in the exhaust manifold with three extensions in alignment with the central dome and the two intake openings, and means for securing said extensions to the cooperating parts in the intake manifold.

3. A device of the kind described comprising the exhaust manifold of an internal combustion engine, a cooperating intake manifold therefor provided with a neck adapted to cooperate with the carbureter, a central opening in the intake manifold positioned substantially above said neck, and a plurality 65 of additional openings in the manifold, in combination with a cooperating pipe positioned within the exhaust manifold with extensions arranged to register with the said central opening and with the other inlet 70 openings, means for connecting said extensions to the inlet manifold, and venturis arranged in the inlet manifold in proximity to the additional inlet openings.

In testimony whereof, I have hereunto 80 signed my name in the presence of two subscribing witnesses.

HARRY S. BENJAMIN.
